UNITED STATES PATENT OFFICE.

CHARLES W. SPONSEL, OF HARTFORD, CONNECTICUT, ASSIGNOR OF ONE-HALF TO CHARLES F. TAYLOR, OF HARTFORD, CONNECTICUT.

MAGNETIC CHUCK.

SPECIFICATION forming part of Letters Patent No. 766,201, dated August 2, 1904.

Application filed February 6, 1904. Serial No. 192,292. (No model.)

To all whom it may concern:

Be it known that I, CHARLES W. SPONSEL, a citizen of the United States of America, residing at Hartford, in the county of Hartford 5 and State of Connecticut, have invented certain new and useful Improvements in Magnetic Chucks, of which the following is a specification.

This invention relates to magnetic chucks 10 or carriers especially designed for use with machines for presenting articles for inspection of the kind set forth in my application filed September 25, 1903, Serial No. 174,577.

Primarily the object of the invention is the 15 provision of a magnetic chuck or carrier for presenting the articles for inspection.

A further object of the invention is the provision of a magnetic chuck or carrier of peculiar construction and one in which the articles received at an angle from suitable conveyer mechanism may be adjusted to present them in proper position for the action of chucks or other devices by which they may be turned for inspection purposes.

25 A further object of the invention is the provision of a magnetic carrier in which the articles to be presented for inspection are held above, but out of contact with, the electromagnets, so that when the circuit controlling 30 the action of the carrier is broken they will not be retained on the carrier by residual magnetism.

A further object of the invention is the provision of notched plates, one of which is movable with relation to the other, so that articles received at an angle to the carrier in the notches of the plates may be adjusted to proper position to enable them to be turned for purposes of inspection.

40 Further objects of the invention will be hereinafter set forth.

In the accompanying drawings, Figure 1 is a plan view of part of a machine for presenting articles for inspection involving my invention. Fig. 2 is an end view of said part of the machine. Fig. 3 is a view corresponding to Fig. 2 and partially in section, showing the position of the magnetic carrier when it receives the articles from the conveyer mech-

anism. Fig. 4 is a view similar to Fig. 3 and 50 also partially in section, showing another position of the carrier. Fig. 5 is a plan view of the carrier, illustrating the articles in the positions they are received from the conveyer mechanism. Fig. 6 is a view similar to Fig. 55 5, showing the articles brought to their proper positions in readiness to be received by the chucks for turning purposes. Fig. 7 is a side view, partially in section, of my invention; and Fig. 8 is a transverse section on line 8 8 60 of Fig. 7.

Like numerals designate similar parts throughout the several views.

Referring to the drawings, the numeral 5 designates framework of any suitable construction in which the magnetic carrier is mounted for operation. This carrier is shown as having trunnions 6, which are journaled in arms 7, keyed or otherwise secured to a rock-shaft 8, which may be operated in any desired 70 way—as, for instance, by a pitman 9, connected with a crank-arm 10, secured to said rock-shaft, as illustrated in Figs. 1 and 7.

Designated by the numeral 12 are conveyer-screws which may be driven either intermittently or continuously in any desired manner to advance articles held between the threads thereof to positions where the carrier may receive them.

Gearing (designated generally by dotted 80 lines at 13 in Fig. 2) is shown as one means by which the conveyer-screws 12 may be rotated in the same direction; but it is distinctly to be understood that the invention is not limited to such gearing, for other means 85 may be employed for driving the screws without departure therefrom.

My improved magnetic carrier is designated in a general way by the numeral 14 and comprises in its preferred form a hollow rectangular frame. Two plates 15 15', of brass or other non-magnetic material, each plate having notches 15² for the reception of the articles to be inspected, constitute the sides of the carrier, and back of these plates are iron 95 or other magnetizable plates 16 16' of less width than the plates 15 15', so that their upper edges will be below the bases of the notches

15², and consequently will not come into contact with the articles to be inspected, but will have their full effect when energized to retain said articles in the notches 15². Said plates 5 15 15' are separated to form a coil-receiving chamber by a central core 17, around which is placed an oblong coil 18, preferably composed of insulated wire of small gage. To inclose and protect the coil, top and bottom plates 10 19 and 20, of brass or other non-magnetic material, are placed between the plates 16 16', and all the parts are firmly secured together by screws 21, passing through the plates 15 15' 16 16' and threaded into the core, as shown 15 in Fig. 8. Trunnions 6 are provided with heads 22 for closing the ends of the coil-chamber, and said heads are grooved at 22' to receive tongues on the plates 19 and 20, as illustrated in Fig. 7.

20 Spools 23, composed of vulcanized fiber or other insulating material, surround and are keyed to the trunnions 6, and the flanges of said spools bear on one side against bearings of the arms 7, and on their other sides against 25 the heads 22 of said trunnions, as illustrated in Fig. 7. Between the flanges of each spool is a metallic contact-ring 24, and the ends of the coil 18, from which the insulating material has been stripped, are inserted within 30 said contact-rings, as also shown in Fig. 7.

Reduced extensions 6' of the trunnions 6 are journaled in bearings 7' of the arms 7, and to the outer one of said extensions is secured a gear-wheel 25, actuated by means hereinafter 35 described.

Rock-shaft 8 is journaled in bearings 26, rising from the frame or stand 5, and, as above stated, this rock-shaft is actuated by a pitman 9, connected to crank-arm 10 by any suitable means—for instance, those illustrated and described in my application above mentioned.

Any suitable means may be utilized for energizing and deenergizing the electromagnets 45 16 16' of the carrier, and in Fig. 1 of the drawings a circuit is designated by 27, said circuit having a switch 28, by which the current may be turned on or off, as required. The terminals of the wires of this circuit are 50 connected with contact-rings 29, insulated from the rock-shaft 8, and connection is made between the contact-rings 24 and said rings 29 by metallic strips 30, supported upon blocks of insulating material 31, secured to and projecting inwardly from the arms 7, as illustrated in Figs. 1 and 7.

For axially rocking the magnetic carrier a toothed sector 32, in engagement with gear 25 on one of the extensions 6', is employed, 60 said sector being at the end of an arm 32', having a hub 32' sleeved upon the shaft 8 between an end collar 33 thereof and the hub of the outer arm 7, and for actuating said sector-arm a rod 34 is articulated to a projection 65 of the arm at one end and may be operated

mechanically or otherwise, as desired. Projecting from a frame or stand 50 is a standard 35, in which is formed a cam-groove 36, adapted to receive a pin 37, secured to the notched plate 15. This plate is provided with slots 70 38, through which the screws 21 pass, and when the pitman 9 is actuated to rock the carrier to the position illustrated in Fig. 3 the stud 37 of said plate will enter the cam-groove 36 and will throw the plate to the position necessary to conform to the inclined location of the nails or other articles upon the conveyer-screws 12, as illustrated in Fig. 5, and as said carrier is rocked back to the position illustrated in Fig. 6 said plate will be 80 actuated by the cam 36 to bring the nails or other articles received by the magnets from the conveyer-screws 12 to the proper positions for the action of the chucks employed for intermittently turning the articles to present them for inspection. These chucks are designated in a general way by 39 and are carried by a slide 40, as illustrated in Figs. 1 and 2 and as fully set forth in my application aforesaid.

90 In the operation of my invention the circuit having been established by the switch 28 or otherwise the magnets are energized and the carrier is actuated to the position illustrated in Fig. 3 to attract the nails or other articles from the conveyer-screws. As it is moved to said position the plate 15 is thrown by cam 36 to the position illustrated in Fig. 5, and the articles are received from the conveyer-screws, and after this has been accomplished the carrier is returned to normal position, where it remains during several of the inspecting periods, as stated in my former application. During this return movement the sliding plate 15 is actuated to bring the 100 articles from the inclined position (illustrated in Fig. 5) to the straight positions, (illustrated in Fig. 6,) where they are held in readiness for the action of the chucks 38.

105 Many changes may be made in the various details of my invention without departure therefrom, and various means different from those shown may be employed for retaining the articles upon the carrier. So, too, other devices may be employed for enabling the 110 carrier to receive the articles in an inclined position from the conveyer-screws and for bringing them to the proper positions to enter the chucks by which they are intermittently 115 turned.

120 Means different from the notches shown for the reception of the articles may also be employed without departure from my invention.

Having thus described my invention, what I claim is—

125 1. A magnetic carrier comprising a body; a coil; an electromagnet; and means on the sides of the carrier, and projecting above the magnet, for preventing the effect of residual magnetism when the magnet is deenergized. 130

2. A magnetic carrier comprising a tubular body, a coil within said body; a device adapted to be energized by the current traversing the coil; and means on the sides of the carrier, 5 and projecting above said device, for preventing the effect of residual magnetism in said device when the circuit of the coil is broken.
3. A magnetic carrier comprising a body; an electromagnet; a non-magnetic device on the side of the body, and projecting above the magnet, for supporting an article within the field of, but not in engagement with, said magnet; and means for energizing and de-energizing said electromagnet.
4. A hollow carrier comprising electromagnets; a coil; and non-magnetic devices on the sides of the carrier, and projecting above the magnets, for supporting an article within the field of, but not in contact with, said 10 nets.
5. A magnetic carrier comprising plates; a coil for energizing said plates; and devices of non-magnetic material on the sides of and projecting above said plates for supporting an article or articles within the field of said 15 plates when energized.
6. A carrier having plates of magnetizable material; an energizing-coil for said plates; and plates of non-magnetic material, the latter having seats to support articles out of contact from said plates.
7. A magnetic carrier having electromagnets; a coil for energizing said magnets; plates of non-magnetic material having notches for the reception of articles to be held by the carrier; and coil-protecting plates.
8. A magnetic carrier having electromagnets; an energizing-coil, plates of non-magnetic material having seats for the reception 20 of articles to be held by the carrier, and insulated trunnions, in combination with supports for said trunnions; and means for actuating said supports.
9. The combination, with a carrier, of plates having seats for the reception of articles; means for moving one of said plates upon said carrier; and a conveyer for delivering articles to said plates.
10. The combination, with a conveyer, of a carrier, a stationary notched plate, a movable notched plate, and means for actuating said movable plate.
11. A carrier having notched plates provided with seats for the reception of articles, 25 combined with means for reciprocating one of said plates, and with means for delivering articles to said plates.
12. The combination, with a magnetic car-
- rier, of devices having seats for the reception of articles upon said carrier; means for rocking the carrier; and means for reciprocating one of said devices with relation to the other.
13. The combination, with a magnetic carrier, having a stationary, notched plate and a reciprocating notched plate, of means for 30 rocking said carrier; and means for reciprocating one of said notched plates.
14. The combination, with conveyer mechanism, of a magnetic carrier having article-receiving plates; means for actuating the carrier toward and from the conveyer mechanism; and means for reciprocating one of said plates to thereby enable the carrier to receive the articles in the positions in which they are held by the conveyer mechanism.
15. The combination, with conveyer-screws for feeding articles at an angle, of a magnetic carrier; notched plates carried by said carrier; means for actuating the carrier toward and from the conveyer-screws; and means for reciprocating one of said notched plates.
16. The combination, with conveyer mechanism, of a carrier; means for rocking said carrier toward and from the conveyer mechanism; notched plates on the carrier, one of which is movable; and a cam for actuating said movable plate.
17. The combination, with conveyer-screws, of a magnetic carrier; means for actuating said carrier toward and from the conveyer-screws; a stationary, notched plate on the carrier; a movable, notched plate also on the carrier; a stud carried by said movable plate; and a stationary cam with which said stud engages upon the movements of the carrier toward and from the conveyer-screws.
18. A carrier provided with devices for the reception of an article, one of said devices being movable with relation to the other, whereby an article received in one position 40 may be adjusted to a different position, combined with a conveyer for delivering articles to said devices.
19. A magnetic carrier provided with plates adapted to receive articles, one of said plates being movable with relation to the other, whereby articles received in one position may be adjusted to another position, combined with means for delivering articles to said plates.

In testimony whereof I affix my signature in presence of two witnesses.

CHARLES W. SPONSEL.
